UNITED STATES PATENT OFFICE

2,591,924

METHOD OF MANUFACTURING HOPPER
CAR FRAME STRUCTUREGeorge B. Dorey, Westmount, Quebec, Canada,
assignor to Enterprise Railway Equipment
Company, Chicago, Ill., a corporation of Illinois

Application December 22, 1947, Serial No. 793,235

1 Claim. (Cl. 29—164)

1

My invention relates to an improved method of manufacturing hopper car frame structures and relates to a type commonly used to accommodate a discharge door.

A specific object of my invention is to provide a welded frame structure incorporating a stirruplike bottom member of heavy construction which can be fashioned to present a rugged marginal reinforcement for a discharge door opening.

My invention further resides in the employment of a heavy stirrup member and in the manner in which it is processed to provide a framing structure with walls extending in different directions.

My invention also resides in the particular manner a bulb angle member is applied in a door frame to make use of the concentration of metal provided by the bulb section in order to mitigate the effects of wear and corrosion.

My invention further resides in certain details of parts such as will be more fully pointed out hereinafter and claimed.

For further comprehension of my invention reference may be had to the accompanying drawings wherein: Fig. 1 is a vertical transverse sectional view taken through a hopper car and showing my improved construction as applied to a hopper on one side of the center sill. Fig. 2 is a vertical longitudinal side view of that portion of the hopper car shown in Fig. 1, said view showing the door in conventional dot and dash lines in open position. Fig. 3 is a fractional sectional elevational view on an enlarged scale taken through the lower portion of the hopper and on a line corresponding substantially to a line 3—3 of Fig. 1. Fig. 4 is a fractional sectional elevational view on an enlarged scale taken through the upper part of the hopper and on a line 4—4 of Fig. 1. Fig. 5 is a vertical elevational view of a frame and door assembly with my improvements as shown detached from the car. Fig. 6 is a vertical elevational view of the assembly shown in Fig. 5 as viewed from left to right. Fig. 7 is a cross sectional plan view taken through the frame and door and as viewed on a line 7—7 of Fig. 5. Fig. 8 is an elevational front view of the stirrup portion of the hopper frame illustrated in Fig. 5. Fig. 9 is a side elevational view of the stirrup shown in Fig. 8 as viewed from left to right. Fig. 10 is a top plan view of Fig. 8. Fig. 11 is a plan view of a rolled structural shape in the form of an angle beam member known as a bulb angle member, said view showing the member prior

2

to being bent to final shape as indicated in Fig. 8, said view being on a reduced scale as compared to the illustrations shown in Figs. 8 to 10 inclusive.

In said drawings my improvements are shown as applied to the so-called W-type of hopper car in which hoppers are disposed in transversely aligned relation on opposite sides of the centersill. Inasmuch as the construction on the opposite sides of the centersill is similar, the description herein will be confined to the structure of only one of the hoppers. In said drawings, the centersill is shown at 10 and the lower portion of a side wall at 11. The hopper structure is defined by inner and outer walls as at 12 and 13 respectively, said walls being spaced transversely from each other and connected by transversely extending upper and lower oppositely sloping floor walls as indicated at 14 and 15 respectively.

The said inner and outer walls 12 and 13 lead upwardly and outwardly from the sloping floor wall 15 on curves 16 of appreciable radius and the outer wall 13 extends at an incline to meet the lower portion of the adjacent side wall 11 whereas the inner wall 12 extends at a comparatively steep angle to meet with the center sill.

Positioned across the open end of the hopper is the frame assembly consisting of the frame A and its associated pivotally mounted door B. The frame A includes a transversely disposed upper member 17 preferably formed of a bulb angle member having the web thereof 18 disposed in underlying relation with respect to the upper sloping floor 14 and having the flange 19 outstanding to form the top wall of a foursided discharge chute defining the sides of the door opening of the frame. The sides and bottom of the discharge chute are formed by the outer portion of a bulb angle member bent in stirrup form to extend around the hopper side and bottom walls. The said stirrup member 20 is formed of a bulb angle member disposed with the web 21 thereof disposed beneath the hopper bottom wall and projects beyond the hopper side walls an appreciable distance to form the lower wall 22 of the discharge chute. The ends of the stirrup member outwardly of the hopper bottom wall are formed with a slot 23 to divide the web in separated sections indicated at 24, 25, 26 and 27 and the inner sections carrying the outstanding flange 28 are bent to overlie the hopper side walls, section 24 being disposed to overlie the side wall 12 and section 25 to overlie outer wall 13 and sections 26 and 27 are extended inwardly of the said over-

lying walls to form the side walls of the chute. The outer margin of the chute walls carry the bulb portion 29 of the stirrup member and thus a well reinforced edge section is obtained for the outer edge of the said bottom and side walls of the chute.

The said sections 26 and 27 have their end edge portion 30 brought into meeting relation with the outstanding flange 19 of the upper member and welded thereto at 31. Similarly the overlying sections 24 and 25 are brought into meeting relation with the ends of the beam 17 and welded thereto at 32 and 33. Outwardly of the discharge opening the outstanding flange 19 of the top member is coped out as at 34 and 35 and triangular shaped floor plates 36 and 37 are disposed adjacent the respective sides of the discharge opening to bridge the space intermediate the opening and hopper side walls, said plates being welded to the respective associated separated sections of the stirrup member and welded thereto as indicated at 38 and 39 in the case of floor plate 36 and at 40 and 41 in the case of plate 37. Said respective plate sections 36 and 37 are further brought into meeting relation with the coped out flange section of the top member and welded thereto as indicated at 42 and 43.

The door B in its closed position abuts the bulb portion 29 of the frame chute lower and side walls, said door being formed with upturned flanges 44 arranged to enclose the chute. The door is hingedly mounted adjacent the upper part of the frame on hinge butts 45 which preferably consist of a pair of plates welded to the top member 17. Said top member 17 is preferably formed of a bulb angle member with the bulb portion 46 at the extreme upper edge of the frame. The concentration of metal at the extreme edge of the frame makes it possible to dispose openings 47 in the web 18 to receive the rounded portion 48 of the hinges of the door and thus permits the disposition of the hinge pivots of the door immediately below the transverse upper wall 14 and allows for favorable hinging conditions.

The placement of the door hinge axis in close proximity to the sloping floor sheet 14 enables the lowering of the said floor thereby providing for an increase in the load carrying capacity of the car without impairing the clearance between the swinging edge of the door and the rail.

The use of the bulb angle member as the top member of the frame with the bulb formation 46 located at the extreme upper edge of the door frame is a factor which makes it possible to dispose the openings 47 in the web without unduly reducing the strength of the beam. In order to coordinate the strength of the bulb formation 46 with the web 18 the hinge butt plates 45 are welded to both the web 18 and the bulb 46.

In the conventional type of car of the character described, it is customary to offset the frame at an angle of approximately 9 degrees from the normal relatively to the bottom hopper wall, as at 49, which results in imparting an undesirable

twist to the door abutting face of the frame during bending of the stirrup. When the latter is formed in one piece the twisting tendency is counteracted in my improved construction by deflecting the lower outer portion of the stirrup as indicated at 50 thereby allowing for the bending of the side walls of the chute about the curved corners in right angular relation. It will also be noted that the side wall portions of the stirrup are bent in such a manner that a twist is necessary as at 51 and 52 in order to conform to the inclination of the hopper side walls. In my improved construction inasmuch as the bending operation of the split stirrup sections is independently effected, it will be evident that considerable distortion of the twisted section of the beam may be made without affecting the alinement of the chute walls. The physical separation of the two parts of the stirrup is of importance in facilitating the manufacture of the complete frame and assuring a uniform and level bearing surface against which the door will abut when in closed position.

What I claim is:

25 Method of manufacturing a frame for positioning around a railway car hopper opening defined by a bottom wall and side walls diverging therefrom so as to provide a discharge opening smaller than said hopper opening, said hopper opening lying in a plane at an obtuse angle to the plane of said bottom wall which comprises: providing a top beam member long enough to extend across the top of said hopper opening, shaping a strap-like member flatwise into a stirrup member so that its cross section conforms to said bottom and side walls, longitudinally splitting the ends of said stirrup member along the portions thereof conforming to said side walls, bending the outer split end portions toward each other in divergent relation to the inner split end portions so as to extend normal to said hopper opening when assembled in juxtaposition thereto to define the sides of said discharge opening, welding the upper ends of said divergent split end portions to the underside of said top beam member, and welding plate members to said divergent split end portions and to the under side of said beam member.

GEORGE B. DOREY.
